DISK HARROW

Alvah E. Rutter, Rockford, Ill., assignor to J. I. Case Company, Racine, Wis., a corporation

Application May 28, 1942, Serial No. 444,818

19 Claims. (Cl. 55—81)

The present invention relates to harrows and more particularly to disk harrows of the so-called "wide" type, and an object of the invention is to generally improve the construction and operation of devices of this class.

A further object is to provide such a harrow which may be narrowed for transport or for other well-known purposes, such for example as operation in hard ground, more expeditiously and with less expenditure of labor than in the case of such harrows heretofore known.

A further object is to provide such a harrow in which when narrowed the weight of idle portions of the harrow is carried in such a position as to facilitate the operation of the remainder of the harrow in hard ground.

A further object is to provide improved draft means for harrows of such characteristics; to provide improved spring means for resisting upward movement of the center of such a harrow; and to provide detailed improvements for the better realization of the above objects.

Further objects and advantages of the invention will become apparent from a consideration of the following detailed description taken in connection with the accompanying drawings wherein a satisfactory embodiment of the invention is shown. However, it is to be understood that the invention is not limited to the details disclosed but includes all such variations and modifications as fall within the spirit of the invention as herein expressed.

In the annexed drawings,

Figure 1 is a front perspective view of such a harrow in "straight" position with parts folded for transport, use in hard ground, or the like.

Fig. 2 is a similar view with the harrow in "angled" position and with the parts unfolded for use at maximum width.

Fig. 3 is an enlarged detail of certain mechanism indicated in Figs. 1 and 2.

Fig. 4 is an enlarged perspective view of a folding connection indicated in Figs. 1 and 2.

Fig. 5 is a similar view with the parts in a different position.

Fig. 6 is a transverse vertical sectional view through certain latch mechanism indicated in Figs. 1 and 2.

Fig. 7 is a longitudinal axial sectional view of the same including portions of a drawbar.

Fig. 8 is an enlarged plan view with parts removed and others broken away of certain mechanism indicated in Fig. 3.

Fig. 9 is a right side elevation of the same.

Fig. 10 is a sectional view taken on the line 10—10 of Fig. 9.

Fig. 11 is a vertical axial sectional view of a spring mechanism indicated in Fig. 3.

Fig. 12 is a detail of certain mechanism indicated in Fig. 1.

As particularly seen in Fig. 2, the harrow of the present illustrative embodiment comprises a pair of gangs generally designated as 10 and 11, connected at the mid portion of the harrow by a hold-down device generally designated as 12. The harrow is propelled by a draw bar generally designated as 13 connected at one end to gangs 10 and 11 in the vicinity of device 12 and having braces or portions 14 and 15 extending from the forward portion of draw bar 13 backwardly and outwardly and engaging gangs 10 and 11 at points towards the outer ends thereof. Gangs 10 and 11 being identical, gang 10 only will be described in detail, it being noted that each of the gangs is made in two sections, 16 and 17 of gang 10, and 18 and 19 of gang 11.

Returning to a more detailed description of the harrow, section 17 of gang 10 comprises a series of disks 20—20 fixed on an axle 21 carried in bearings 22, 23 and 24 (Fig. 3). The disks and axle being of well-known form, need not be further described. Bearing 22 has a standard 25 extending upwardly therefrom to members 26 and 27, Fig. 1, connected by a panel 28 forming a frame or weight box above disks 20. A similar standard 29 extends upwardly from bearing 23 and a third standard 30 extends upwardly in similar manner from bearing 24. A unitary section, above designated as 17, is accordingly provided. Section 18 is identically similar, as previously stated.

Sections 17 and 18 as so far described, connected with draw bar 13 and braces 14 and 15 provide a harrow which would be suitable for hard ground and difficult conditions, and not too wide to pass through the ordinary farm gate. This is not as wide as desirable under most conditions and for which reasons sections 16 and 19 are used.

Referring to Figs. 1 and 4, panel 28 stops short of standard 25 and a cross member 31 extends between members 26 and 27, in the present instance the major portion of the cross member being inclined outwardly and downwardly. Member 31 serves to connect above mentioned section 16 with above mentioned section 17. Thus section 16 has frame members 32 and 33 joined by a panel 34, standards 35 and 36 connecting with bearings 37 and 38 carrying an axle 39 on which are fixed disks 40—40. Members 32 and 33 extend inwardly from panel 34 in telescoping or nesting relation to above mentioned members 26 and 27.

respectively, then bending upwardly at approximately the inclination of above mentioned member 31. They are joined by a cross member 41 which preferably overlies member 31 at substantially the same angle. A pin or bolt 42 traverses members 41 and 31 in the present instance approximately in the middle thereof and serves as a pivot about which member 41 may rotate on member 31 to provide for displacement of section 16. Owing to the nesting relation of members 32 and 33 within members 26 and 27, in conjunction with the pivotal connection afforded by bolt 42, section 16 is maintained substantially in alignment with section 17 so as to form a continuation thereof. The addition of section 16 and identical above mentioned section 19, to above mentioned sections 17 and 18, provides a harrow of sufficient width to fully load the tractor and accomplish a satisfactory amount of work.

Sections 16 and 19 may be readily removed from alignment with sections 17 and 18 as will now appear. Bolt 42 preferably has a somewhat loose fit in members 31 or 41, or both, and is encircled by a spring 43 compressed between member 41 and a nut 44, a washer 45 being interposed if desired. Ordinarily, misalignment of sections 16 and 17 would be impossible because of the nesting relation of members 33 and 32 in members 27 and 26. Due to the freedom provided by spring 43, however, section 16 may be lifted slightly so as to cause members 33 and 32 to clear member 27 whereupon section 16 may be rotated backwardly about bolt 42 as a pivot. Referring now to Fig. 5, owing to the contact between cross members 31 and 41, section 16 moves in a plane inclined inwardly and upwardly toward the center of the machine. This is partly accomplished in Fig. 5 and it will be noted that the total movement of section 16, while being quite substantial, namely, half of the circumference of a circle with bolt 42 as a center, referring to any point on section 16, the actual upward movement is very gradual and in effect is only sufficient to bring section 16 to its elevated position above section 17 as seen in Fig. 1. Unlike devices of the prior art, it is unnecessary in the device of the present invention to lift section 16 bodily substantially at all, and in any event only sufficiently to disengage member 33 from member 27. The operator has the benefit of the principle of the inclined plane and by virtue of the relatively long distance which he moves section 16, need exert only a fraction of the force necessary to bodily lift section 16.

As a practical matter, a boy may easily shift section 16 from the position shown in Fig. 2 to that shown in Fig. 1, whereas with known constructions, it is difficult even for a very strong man to effect the change from wide to narrow position. Furthermore, the movable section is under full control at all times and has no tendency to "get away" from the operator and cause injury. In the present embodiment, the force of gravity assists in restoring section 16 to the lowered position shown in Fig. 2. Spring 43 is preferably adjusted to cause sufficient friction between members 31 and 41 to prevent spontaneous movement of section 16, and maintains the desired relation between portions 41 and 31. It must therefore be helped a little in its downward course and produces no dangerous condition at any time.

A further advantage lies in the fact that section 16 never turns completely over, disks 40 always being under frame members 32, 33 and

panel 34 to some extent, as opposed to prior art devices in which the pivoted section turns completely over with the frame below and the sharp dangerous disks above and exposed. Besides having the disks below the frame in the present instance, it is unnecessary to struggle to the utmost of one's strength to shift the section and there is never the likelihood of the section getting out of control and falling on or against the operator.

In operation, of all disk harrows, there is a strong axial end thrust. In the present instance, sections 10 and 11 oppose each other and the end thrust is neutralized at the center of the harrow. However, end thrust developed in section 16 must be directed to section 17, and for practical reasons in the present instance this thrust is transmitted to members 33 and 32, ultimately manifesting itself in cross member 41. There would be therefore a tendency to shear bolt 42. To avoid this, member 41 is shouldered downwardly at 46 and has a flange portion 47 curved upwardly at 48 and 48a to provide cam portions. Inward thrust of section 16 is accordingly transmitted through shoulder 46 to member 31 and accordingly to inner section 17.

When section 16 is swung rearwardly as above described, cam portion 48 rides up over member 31 compressing spring 43. In view of the substantial leverage afforded by the length of section 17, this slight resistance to rearward turning is not noticeable to the operator. With section 16 at rest on top of section 17, flange 47 rests on member 31. This affords a substantial sliding surface and avoids damage to member 31 and shoulder 46 during the rotating movement. It is to be noted that section 16 need not necessarily be rotated rearwardly in folding or unfolding, but may be rotated forwardly if desired, in such case the cam surface 48a serving to raise member 41 so that shoulder 46 will clear member 31. There are thus two alternative ways of folding the harrow, although in general it is desirable to rotate the sections to the rear where the operator is clear of all parts of the implement.

This property of the construction is another distinct improvement over the prior art, in which it is necessary to climb on top of the harrow in order to get sufficient purchase to lift the folding section.

Another advantage of the above described property is that the outer section 16, while normally remaining positively in line with member 17, will be lifted in the event that it strikes a substantial obstruction in the ground. This will free member 33 from member 27 whereupon the rearward reaction of the ground and the obstruction will cause member 16 to swing to the rear and relieve the parts of any dangerous stresses. Shoulder 46 therefore constitutes and serves the purpose of a detent for yieldingly holding sections 16 and 17 in line.

Section 16 may be positively locked in operating position if desired by placing a pin or the like 49 in a hole 50 which is aligned with a hole 51. Fig. 5, in member 31 in the working position of the parts, the pin being removed when it is desired to fold the harrow. In like manner section 16 may be locked in its upper or folded position by replacing pin 49 in a hole 52 which in the present instance lines up with hole 51 in the folded position. Hole 50 may be arranged to line up with a hole 53 in the folded position and hole 52 may align with hole 53 in the working

position, all as indicated in Fig. 5. If desired, a second pin 54 may be inserted in the remaining set of aligned holes as will be understood.

Owing to the freedom of bolt 42, section 16 is free to rise somewhat, about bolt 42 as a pivot, in operation in rough ground, and it may also fall approximately about the end of members 27 and 28 by compressing spring 43 and raising pins 48 and 54, if they are used. As will be apparent the nesting relation between members 33 and 32 within members 27 and 28 may be relied upon to maintain the gang sections in alignment without other assistance.

In so far describing the folding device of the harrow, suitable draw bar and angling mechanism is presumed. In the disclosed embodiment above mentioned draw bar 13 comprises a forward section 55, Fig. 1, which is slidably or telescopically arranged between members 56 and 57, comprising a rear or relatively stationary section of draw bar 13. Members 56 and 57 are connected, as will appear, to above mentioned bearing 24 and to a bearing 58 related to gang section 18 in exactly the same manner as bearing 24 is related to section 17. Draw bar section 55 is pivotally connected at 59 to above mentioned brace 14. Brace 14 extends rearwardly and outwardly in the direction of bearing 22. However, to reach bearing 22 it would have to pass through one of disks 20, specifically disk 20a, which of course is impossible. Brace 14 accordingly has a lower portion which is offset at 60 to pass around disk 20a and engage bearing 22 beyond disk 20a. The major portion of brace 14, however, proceeds in a straight line from pivot 59 toward bearing 22. A straight pull is also transmitted from member 14 by an upper section 61 which angles upwardly from a pivotal attachment 62 to a pivot 63 on a portion of standard 25 and preferably directly over a pivot 64 on which offset portion 60 is connected to bearing 22. In this manner a substantially straight line pull is exerted on the end of portion 17 and in the region of bearing 22. A substantially identical construction is used in connection with brace 15, the latter having an offset portion 65 pivotally connected at 66 with a bearing 67, and an upper section 68 pivotally connected at 69 with brace 15. Portion 68 is also pivotally connected at 70 with a portion of a standard 71 connected with bearing 67. Brace 15 is pivotally connected at 72 with above mentioned front portion 55 of draw bar 13.

Draw bar portion 55 may be locked in its relation to portions 56 and 57 by a latch mechanism generally designated as 73, fixed with above mentioned members 56 and 57, the latch having a trip rope or member 74 extending to a convenient point for manipulation by an operator. Latch 73 has a pin 75 engageable in one or another of holes 76—76 for maintaining the parts in desired adjustment. Fig. 1, as above noted, shows the harrow in "straight" position as it would be transported to and from the field. To angle the harrow, assuming a tractor, not shown, attached to a pin 77 of draw bar 13, it is merely necessary to pull trip rope 74 and drive ahead, whereupon portion 55 slides relatively to members 56 and 57, pulling on braces 14 and 15 but not on portions 56 and 57. This results in pulling the outer ends of gangs 10 and 11 forwardly relatively to the inner ends, thus placing the harrow in angle. When the desired degree of angle is achieved, rope 74 is released whereupon latch pin 75 engages the next hole of the series 76.

This arrests the angling movement and transmits the pull of the tractor also to the inner end portions of gangs 10 and 11, whereupon the harrow moves forward in whatever angular position is determined by the particular hole engaged by pin 75. It will be apparent that this operation is true whether the sections 16 and 18 are folded as shown in Fig. 1 or in working position as shown in Fig. 2. To restore the harrow to straight position, the tractor is backed while trip rope 74 holds latch pin 75 disengaged, portion 55 of draw bar 13 sliding between members 56 and 57 so that braces 14 and 15 receive the backward thrust and tend to move the outer ends of gangs 10 and 11 backwardly relatively to the inner ends.

Returning to a more detailed description of draw bar 13, members 56 and 57, as shown in Fig. 6, are united in the region of latch mechanism 73 by an upper plate 78 and a lower plate 79, making a box-like enclosure at the forward end of members 56 and 57 through which member 55 may slide. As seen in Fig. 7, a plate 80 is extended between members 56 and 57 spaced rearwardly from plate 78. This prevents upward movement of the rear end of member 55 and tends to keep it in line with members 56 and 57. Member 55 has fixed therewith at its rear end, as by a bolt 81, a plate 82 in the present instance having upwardly offset portions as 83 engaging the upper surface of members 56 and 57. This prevents downward movement of the rear end of member 55, the result of the arrangement being a relatively easily telescoping or sliding support between the front and rear sections of the draw bar.

Latch mechanism 73 is built on plate 78. A U shaped member 84 is inverted and fixed with plate 78 and has an upper section 85 which is apertured for the sliding passage of latch pin 75. Plate 78 is also apertured for such passage of pin 75, the apertures being aligned so as to guide pin 75 in a substantially vertical direction and brace it against the very considerable side thrust set up in the draw bar. Latch pin 75 has a cross pin 86 extending laterally thereof and a shoulder 86a against which bears a spring 87 compressed between the shoulder and upper section 85. This tends to maintain latch pin 75 in its downward position. Cross pin 86 also engages ears 88 and 89 of a U shaped yoke or lifter 90 enclosing U shaped portion 84, and resting upon plate 78. Portion 90 has an upstanding inclined arm 91 to which is fastened above mentioned trip rope 74. Spring 87 holds latch pin 75 in its lowermost position and holds member 90 down on plate 78. A pull on rope 74, however, tilts member 90 about pin 86 as a pivot, forward cam portions as 92 engaging plate 78, and raising cross pin 86, thereby compressing spring 87 and raising latch pin 75. This disengages pin 75 from any of holes 76 and allows portion 55 to slide relatively to portions 56 and 57. With rope 74 released, pin 75 will be forced into the next hole 76 which comes beneath it.

Portions 56 and 57, as more particularly seen in Fig. 3, extend rearwardly to the region of bearings 24 and 58 and are united by a plate 93 and further rearwardly by a yoke 94, Fig. 8, having ears 95 and 96. An extension member 97 is connected with member 56 by a bolt or the like 98 and extends outwardly and rearwardly past ear 95 and to which it is connected by a bolt 99. Member 97 continues rearwardly and has an eye portion 100 pivotally engaged with a pin or stud 101 extending in the present instance upwardly

from above mentioned bearing 24. This forms a connection between draw bar 13 and the inner end of gang 10 as above outlined. In similar manner, a member 102 extends rearwardly from bolt 98, is connected with ear 96 by a bolt 103 and has an eye portion 104 embracing a pin or the like 105 on above mentioned bearing 58. This establishes a connection between draw bar 13 and the inner end of above mentioned gang 11. The connection of members 97 and 102 at spaced points, as for example at bolt 98 and at ear 95 or 96 establishes a sturdy rigid connection between members 97 and 102 and the remainder of draw bar 13. In this manner a bifurcated rear portion is provided for the draw bar.

Member 97 has an outwardly extending bracket 106 for cooperation with a hold-down device above generally designated as 12, as will appear, member 102 being provided with a similar bracket 107.

With the mechanism so far described, a connection to the inner ends of the gangs is afforded and the angling action above described can be readily obtained. In disk harrows of this general type, there is also a tendency for the outer ends of the gangs to cut deeper than the inner ends. In the present instance this is eliminated as follows.

Referring particularly to Fig. 3, a compression spring generally designated as 108 exerts an outward pressure against levers 109 and 110 which in turn exert an inward pressure on the upper portions of gangs 10 and 11. Since the inner disks of gangs 10 and 11 contact each other through bumpers 111 and 112 (Fig. 1), considerably below levers 109 and 110, a couple is set up tending to depress the inner ends of gangs 10 and 11 and raise the outer ends thereof. Proper adjustment of spring 108 will then balance this couple and accordingly the tendency to "dig in" of the inner disks.

Returning to a more detailed description of hold down device 12, levers 109 and 110 are fulcrumed on pins 113 and 114, the levers in the present instance being provided with offset ears 115 and 116. Pins 113 and 114 are carried by a cross arm 117, in the present instance bifurcated and suitably fixed as by welding with a tongue 118. Tongue 118 extends from cross member 117 forwardly and downwardly, being arched over spring 108 and having an ear 119 engaged with above mentioned plate 93 by a bolt or the like 120. Tongue 118 is connected by a brace 121 (see also Fig. 9) with above mentioned yoke 94, which gives a stable support for tongue 118. Tongue 118 extends rearwardly approximately to the rearmost extent of the harrow and may be used for the connection of any other desired implement to follow or trail behind the disk harrow, for example, a spike tooth harrow, not shown.

Lever 109 is pivoted at 122 to a cross member 123 constituting a part of above mentioned standard 30 and lever 110 is similarly pivotally connected at 124 with a cross member 125. As will now be apparent, outward pressure of spring 108 will cause inward pressure in pivots 122 and 124.

Bumpers 111 and 112, Fig. 1, are of suitable or well-known construction comprising semi-spherical bodies which roll in contact with each other. Theoretically the surfaces will roll together and each will transmit the end thrust of its respective gang to the other. Owing to rough ground, the necessarily flexible construction of the implement, and unavoidable inaccuracies, these bumpers sometimes become momentarily displaced whereupon one bumper will tend to climb some-

what on the other, thus throwing the inner ends of the gangs 10 and 11 out of line. Levers 109 and 110 are utilized to combat this tendency. Thus, as seen in Fig. 10, lever 109 has a downwardly extending ear 126 to which is pivoted at 127 a link 128. Link 128 in turn is pivoted at 129 to above mentioned ear 106 on member 97. In like manner lever 110 has an ear 130 pivoted at 131 to a link 132 in turn pivoted at 133 to above mentioned ear 107 on member 102.

As will now be apparent, undesired relative up-and-down movement between cross members 123 and 125 will cause opposite movement of the portions of levers 109 and 110 beyond fulcrums 113 and 114. This, however, will be strongly resisted by links 128 and 132 which will not permit such movement without imparting a twisting motion to draw bar 13. Thus, although all the parts are ordinarily somewhat flexible, any climbing tendency of bumpers 111 and 112 is very strongly resisted by this construction.

Spring 108 as more particularly shown in Fig. 11, is disposed about a sleeve 134 suitably fixed as by welding to a bifurcated element 135. Within sleeve 134 is guided a rod 136 also extending into spring 108. In the present instance rod 136 has fixed therewith a bifurcated member 137 and an abutment 138 is suitably fixed, in the present instance as by threading, on rod 136. Thus, the expansion of spring 108 tends to force rod 136 out of sleeve 134, thus increasing the distance between bifurcated members 135 and 137. The force of this outward pressure can be varied by adjusting abutment 138 along rod 136.

Returning to Fig. 3, bifurcated member 135 is pivoted as by a pin 139 to above mentioned lever 110 beyond link 132 and in similar manner bifurcated portion 137 is pivoted to lever 109 beyond link 128 by a pin 140. Among other advantages of this construction, a compression spring is utilized in order to pull the upper portions of gangs 10 and 11 together. This is a more rugged and durable construction than any arrangement which would place a spring in tension.

A detail of standard 30 and its associated parts is shown in Fig. 12. As will be apparent, stud 101 extends upwardly from bearing 24 and is shouldered at 141. Ear 100 is journaled on stud 101 between bearing 24 and a lower portion 142 of standard 30. A bolt or stud 143 also extends from bearing 24 and traverses portion 142, nuts 144 and 145 holding portion 142 firmly in contact with shoulder 141 and bearing 24. Standard 30 also includes above mentioned cross member 123 to which is pivoted, by means of above mentioned pin 122, lever 109. In the present instance, a member 146 is suitably fixed with cross member 123 as for example by welding and receives pin 122 therethrough; this reinforces the connection of lever 109 with cross member 123.

As will be understood, the construction associated with bearings 22, 58 and 87 is substantially identical with that just described and no further detailed description of the latter parts is deemed necessary.

The operation of the invention is thought to be clear from the above description. Sufficient to say, the harrow may be placed in angle by pulling trip rope 74 and driving ahead. Conversely it may be straightened by pulling trip rope 74 and backing the tractor. End sections 16 and 19 may be readily folded by rotating either backwardly or forwardly. When in folded position, end sections 16 and 19 are predominately

over the inner ends of sections 17 and 18, whereby to assist under difficult conditions in holding down the middle of the harrow.

In ordinary operation, the tendency toward expansion of spring 108 acts through levers 109 and 110 to draw together the upper portions of the main gangs 18 and 11, thus tending to force the center of the harrow down or in any event to resist upward movement thereof. Levers 109 and 110 act also to prevent or minimize any tendency toward climbing of the inner bumpers, and a supplemental implement may be readily drawn behind the harrow by attachment to tongue 118.

The above being a complete description of an illustrative embodiment of the invention, what is claimed as new and desired to be secured by Letters Patent of the United States is:

1. In a disk harrow, the combination of a pair of gangs, one of said gangs comprising an inner gang section and an outer gang section, means for joining said outer gang section to said inner gang section including a pivotal connection, said connection being inclined from the vertical and horizontal when said harrow is on level ground so that said outer gang section will be raised and folded on top of said inner gang section when said outer gang section is rotated about said pivotal connection, and means independent of said pivotal connection for transmitting the inward thrust of said outer gang section to said inner gang section.

2. In a disk harrow, the combination of a pair of gangs, one of said gangs comprising an inner gang section and an outer gang section, means for joining said outer gang section to said inner gang section including a pivotal connection, and said connection being inclined from the vertical and horizontal when said harrow is on level ground so that said outer gang section will be raised and folded on top of said inner gang section when said outer gang section is rotated about said pivotal connection.

3. In a disk harrow the combination of two disk gangs, draft means connected therewith, and means for changing the angle between said gangs, and one of said gangs comprising two sections pivotally connected for relative movement in a plane inclined from the vertical and horizontal when the harrow is on level ground.

4. In a disk harrow, the combination of two disk gangs, draft means connected therewith and means for changing the angle between said gangs, and one of said gangs comprising inner and outer sections, said outer section being guided for folding movement relatively to said inner section in a plane inclined from the vertical and horizontal when the harrow is on level ground.

5. In a disk harrow the combination of a pair of gangs, each of said gangs comprising two axially aligned sections, and means connecting the two sections together at a single pivot point above the axis of the sections whereby the inward reaction of the outer section is transmitted to the inner section above the axis of the disks thereon, said pivot being so disposed as to provide for forward and rearward swinging of one of said sections relatively to the other.

6. In a disk harrow, the combination of a pair of gangs, one of said gangs comprising an inner gang section and an outer gang section, means for joining said outer gang section to said inner gang section including a plate on the inner gang section and a plate on the outer gang section, said plates being juxtaposed, a pivotal connection for said plates, a shoulder on one of said plates posi-

tioned to engage the other plate for transmitting end thrust developed in said outer gang section to said inner gang section through said plates independently of said pivotal connection.

7. In a disk harrow the combination of a pair of gangs, one of said gangs comprising an inner gang section and an outer gang section, means for joining said outer gang section to said inner gang section including a pivotal connection, said connection being inclined from the vertical and horizontal when said harrow is on level ground so that said outer gang section will be raised and folded on top of said inner gang section when said outer gang section is rotated about said pivotal connection, the dimensions of said outer section being so chosen that said outer section will be positioned vertically above the inner ends of said inner sections when so folded thereover.

8. In a disk harrow the combination of two oppositely extending disk gangs, means for changing the angle between said gangs, each of said gangs comprising two sections connected together for swinging movement in a plane inclined from the vertical and horizontal when the harrow is on level ground whereby the outer section can be swung upwardly and over upon the inner section, the dimensions of said outer sections being so chosen that said outer sections will be positioned vertically above the inner ends of said inner sections when so folded thereover.

9. In a disk harrow the combination of a pair of gangs, one of said gangs comprising an inner gang section and an outer gang section, means for joining said outer gang section to said inner gang section including a plate on the inner gang section and a plate on the outer gang section, said plates being juxtaposed and rotatably connected for movement in their own planes, and said plates being disposed substantially parallel to a plane that is inclined relatively to the vertical and horizontal when said harrow is on level ground so as to raise said outer gang section when the latter is rotated about the rotatable connection.

10. In a disk harrow, the combination of a pair of gangs, one of said gangs comprising an inner gang section and an outer gang section, means for joining said outer gang section to said inner gang section including a plate on the inner gang section and a plate on the outer gang section, said plates being juxtaposed, a pivotal connection for said plates, and a detent on one of said plates positioned to engage the other plate for transmitting a draft from the inner to the outer section, and said detent being so disposed as to be disengaged when said outer section encounters an obstruction.

11. In a disk harrow, the combination of a pair of gangs, one of said gangs comprising an inner gang section and an outer gang section, means for joining said outer gang section to said inner gang section including a plate on the inner gang section and a plate on the outer gang section, said plates being juxtaposed, a pivotal connection for said plates, and a detent on one of said plates positioned to engage the other plate for transmitting draft from the inner to the outer section, said detent being so shaped as to be disengaged by upward movement of said outer section upon encountering an obstruction.

12. In a disk harrow the combination of a pair of gangs, one of said gangs comprising an inner and an outer gang section, said inner gang section having an upper frame including spaced upstanding rims, said outer gang sections also hav-

ing an upper frame, means for joining said outer gang section to said inner gang section including a pivotal connection, said connection being inclined from the vertical and horizontal when said harrow is on level ground so that said outer gang section will be raised when it is rotated about said pivotal connection, and folded on top of said inner gang section, said spaced upstanding rims being extended outwardly past said pivotal connection, and said outer gang section upper frame extending and being engaged between said upstanding rims whereby draft is transmitted from said inner to said outer gang sections.

13. In a disk harrow, the combination of a pair of gangs, one of said gangs comprising an inner gang section and an outer gang section, pivot means connecting said sections for relative forward and backward movement, each of said sections including an upper frame characterized by an upstanding rim, and the rim on one of said frames being positioned to interengage with the rim on the other frame to transmit the draft from one gang section to the other, but being disengageable therefrom to allow relative displacement of said gang sections in the event said gang section encounters an obstruction.

14. In a disk harrow, a pair of gangs, a pivotal connection between the gangs, and a draw bar connected to said gangs at said pivotal connection, said gangs having upper frames and disks, the disks of said gangs being so disposed as to abut in the neighborhood of said pivotal connection for the purpose of neutralizing the end thrust developed in said gangs, and means for urging said upper frames toward each other comprising forwardly extending levers pivotally connected to said upper frames, link means connecting said levers and on which said levers are fulcrumed, a compression spring interposed between said levers forwardly of said link means and acting to force the forward portions of said levers outwardly whereby to urge the connections of said levers to said upper frames inwardly to counteract any tendency for the inner ends of said gangs to rise, and means connected with said levers serving to prevent up-and-down movement of said levers relative to each other for preventing climbing of one of said disks on the other.

15. In a disk harrow a pair of gangs, a pivotal connection between said gangs and a draw bar connected to said gangs at said pivotal connection, said gangs having upper frames and disks, the disks of said gangs being so disposed as to abut in the neighborhood of said pivotal connection for the purpose of neutralizing the end thrust developed in said gangs, means for urging said upper frames toward each other, and mechanism associated with said means serving to prevent climbing of one of said disks on the other.

16. In a disk harrow, a pair of gangs, a pivotal connection between the gangs, and a draw bar connected to said gangs at said pivotal connection, said gangs having upper frames and disks,

the disks of said gangs being so disposed as to abut in the neighborhood of said pivotal connection for the purpose of neutralizing the end thrust developed in said gangs, and means for urging said upper frames toward each other comprising forwardly extending substantially straight levers pivotally connected at one end to said upper upper frames, substantially straight transverse link means connecting said levers intermediate their ends and on which said levers are fulcrumed, and a compression spring interposed between said levers forwardly of said link means and adapted to force the forward portions of said levers outwardly whereby to urge the connections of said levers to said upper frames inwardly to counteract any tendency for the inner ends of said gangs to rise.

17. In a disk harrow, a pair of axially opposed disk gangs, a draw bar pivotally connected to the adjacent ends of said disk gangs, said disk gangs having upper frames, mechanism for urging said upper frames toward each other including a pair of forwardly extending levers pivotally attached to said upper frames and extending on either side of said draw bar, a rearwardly extending draft tongue attached to said draw bar and extending rearwardly between said gangs, a link member carried by said tongue and to which said levers are fulcrumed, and spring means connected with said levers and adapted to urge them in a direction tending to force said frames together.

18. In a disk harrow having a draw bar including spaced apart stationary sections and a slideable section arranged between the stationary sections, the combination of a spacing plate for said spaced apart sections, a latch pin slidably supported in said spacing plate and in one position engaging said slideable portion, guiding means for maintaining said latch pin in predetermined relation to said spacing plate during sliding movement of said latch pin, a fulcrum on said latch pin on the opposite side of said spacing plate from said slideable portion, a lever pivoted on said fulcrum and having a free end engageable with said spacing plate, and means for rocking said lever for engaging said free end with said spacing plate and raising said fulcrum and latch pin for disengaging said pin from said slideable portion.

19. In a latch structure, a plate, a shouldered latch pin slidably supported in said plate, guiding means for maintaining said pin in predetermined relation to said plate during sliding movement of said latch pin, resilient means engaged between said guiding means and the shoulder on said pin for yieldably maintaining said pin in one position, a fulcrum on said latch pin, a bifurcated lever having portions extending on either side of said pin and engaged with said fulcrum, said lever portions having free ends engageable with said plate and means for rocking said lever for engaging said free ends with said plate and moving said fulcrum and said pin against the pressure of said resilient means.

ALVAH E. RUTTER.
